UNITED STATES PATENT OFFICE.

EDWIN JAMES EDDY, OF OTAHUHU, AUCKLAND, NEW ZEALAND.

COLLAPSIBLE CORE FOR HOLLOW CONCRETE WALLS.

Application filed August 2, 1921. Serial No. 489,225.

To all whom it may concern:

Be it known that EDWIN JAMES EDDY, citizen of the Dominion of New Zealand, residing at Favona Road, Mangere, Otahuhu, in the Provincial District of Auckland, has invented certain new and useful Improvements in Collapsible Cores for Hollow Concrete Walls, of which the following is a specification.

10 This invention relates to cores used in the formation of hollow concrete walls, and has for its object the provision of an improved core capable of being easily placed in position, and which is also readily collapsed and 15 removed, as the moulded concrete sets.

According to the invention, the core is formed with two separate sides of suitable dimensions adapted to be kept apart the required distance by adjustable means so that 20 when placed in position in the wall boxing or mould, spaces of the desired width are provided at each side of the core between the latter and the wall boxing, for moulding the outer and inner thicknesses or shells of 25 the wall.

Each side of the core has hinged to the inside of each end one or more vertical pieces adapted to fold inwards, the vertical pieces hinged to the same side being the 30 same shape.

The shape of the vertical pieces hinged to the core sides, is such that both of the pieces attached to one side must be turned inwards to permit said side to be moved towards the 35 other core side when it is desired to remove the core. After one core side has been removed the removal of the other side in a similar manner is a comparatively simple matter.

40 The means for keeping the core sides apart during the moulding of the wall, comprise horizontal plates, hinged at one end to the core side last removed from the mould, and provided with holes adapted to pass upon 45 screwed studs projecting from the sides of the vertical pieces attached to the other core side, and facing each other. Wing nuts screwing on said studs hold the plates on the studs during moulding operations.

Cover plates are also provided at the ends and top of the core for preventing the entrance of concrete between the sides thereof.

The invention will be further described with reference to the accompanying drawing, wherein:—

55

Figure 1 shows the core in elevation.

Figure 2 is a sectional plan of same.

Figure 3 a vertical section and

Figure 4 an end view, while

Figure 5 is an enlarged part sectional plan showing one of the distance plates.

The sides 1, 2 are made of wood, metal or the like and are of a size which permits them to be readily handled in setting up the core box and in removing same from a wall in 65 the course of or at the completion of the formation of the latter.

The side 1 has vertical pieces 3 hinged to the inside of its ends, to fold inwards, and the side 2 has vertical pieces 4 hinged to the 70 inside of its ends, to also fold inwards.

The hinged vertical pieces 3, 4 are shaped so that when the core is set up in position in the wall mould or boxing, the pieces 4 must be swung inwards before the pieces 3 75 can be swung inwards on their hinges.

The sides 1, 2 are kept apart by horizontal plates 5 one or more at each end of the core, said plates 5 being hinged at one end to the side 1 adjacent the vertical end pieces 3. 80

The plates 5 are provided with holes 6 adapted to be passed upon screwed studs 7 provided with wing nuts 8, and which project horizontally from the sides of the vertical end pieces 4 facing each other, when 85 said pieces 4 are in the position shown in the drawing.

By adjusting the plates 5 on the studs 7 the distance between the sides 1 and 2 can be increased or lessened, so as to regulate 90 the spaces between the core sides and the wall boxing or mould in order to obtain inner and outer concrete shells of the desired thickness.

The ends of the sides 1 and 2 are curved 95 as shown and stop short of the pieces 3, 4, when the latter are opened out while in the lower edges of said sides, openings 9 are

provided to allow of wall ties being placed in position to unite the inner and outer shells of the wall.

The vertical end pieces 3 have attached 5 to their outer sides vertical plates 10, which when the pieces 3, 4 are in the positions shown cover and protect the joints or spaces between said end pieces 3, 4. These plates 10 are not attached to the end pieces 4.

10 In use the core is erected with its sides 1 and 2 the required distance apart inside the boxing in which the wall is to be or is being formed. Wall ties are placed across the mould and are accommodated in the openings 9.

The thumb screws 8 hold the plates 5 securely on the studs 7 projecting from the end pieces 4 hinged to the side 2.

20 The plates 5 being hinged at their other ends to the side 1, the sides 1 and 2 are thereby rigidly held apart, with the end plates 10 covering the joints or spaces between said end pieces 3 and 4.

A cover 14 is placed on the top of the 25 core to prevent concrete from passing downwards between the sides 1 and 2. This cover 14 has on its under side a strip 14^a which projects between and serves as a spreader to the sides 1, 2, and also to the pieces 4.

30 When the concrete has set sufficiently, the thumbscrews 8 are removed, and the plates 5 swung off the studs 7, and back against the side 1.

The vertical end pieces 4 can then be 35 swung or folded inwards against the side 2 the sloped surfaces 12 and rounded outer corners of said pieces 4, together with the sloped surfaces 13 of the pieces 3, making it necessary to swing back the end pieces 4 before the end pieces 3. Following on this 40 the cover plates 10, are therefore secured only to the end pieces 3.

With the end pieces 4 swung or folded back, sufficient clearance is provided between the side 1 and shell of the wall to 45 permit the side 2 to be easily removed and once this is done ample working space is provided for the removal of the side 1,

after the end pieces 3 and plates 10 have been swung inwards.

50

What I do claim and desire to obtain by Letters Patent of the United States is:—

1. A collapsible core for hollow concrete walls, comprising separate sides, hinged end pieces carried by each side, adapted to swing inwards, distance plates attached to one side, and studs on the hinged end pieces of the other side adapted to engage the distance plate, substantially as described and illustrated.

2. A collapsible core for hollow concrete walls according to claim 1, wherein the distance plates are hinged at one end to a side, and contains holes adapted to pass upon screwed studs, provided with wing nuts, 65 said studs projecting horizontally from the facing sides of end pieces substantially as described and illustrated.

3. A collapsible core for hollow concrete walls, according to claim 1, wherein the 70 hinged end pieces are shaped, so that the pieces hinged to one core side must be swung inwards to permit the end pieces hinged to the other side to be swung inwards, substantially as described and illustrated.

4. A collapsible core for hollow concrete walls, according to claim 1, wherein the hinged end pieces, last swung inwards have attached thereto, vertical plates adapted to cover the joints or spaces between the end 80 pieces of opposite sides, when the core is set up, substantially as described and illustrated.

5. A collapsible core for hollow concrete walls comprising separate sides, end pieces 85 carried by each side and mounted to swing thereon, distance plates attached to one side, and retaining means carried by the end pieces of the other side adapted to engage said distance plates.

In testimony whereof I have affixed my signature in presence of two witnesses.

EDWIN JAMES EDDY.
